UNITED STATES PATENT OFFICE.

HIRAM H. SPONENBURG, OF WADSWORTH, ILLINOIS, ASSIGNOR OF ONE-HALF TO EDWARD LAAS, OF CHICAGO, ILLINOIS.

RAILWAY RAIL-STAY.

No. 843,710.

Specification of Letters Patent.

Patented Feb. 12, 1907.

Application filed October 29, 1906. Serial No. 341,020.

To all whom it may concern:

Be it known that I, HIRAM H. SPONENBURG, a citizen of the United States, residing at Wadsworth, in the county of Lake and State of Illinois, have invented certain new and useful Improvements in Railway Rail-Stays, of which the following is a specification.

This invention relates to devices for preventing the longitudinal creeping of railway rails over their supporting cross-ties.

The object of this invention is the production of a rail-stay in which the two rail-gripping jaws are provided with means whereby these jaws are guided in their movement toward each other when the same are drawn together to cause them to grip the rail between them. This guiding may be either to minimize the tilting strain on the jaws when drawn toward each other or to prevent lateral displacement of the jaws relative to each other or for other purposes.

In a preferred form of the invention I have shown the jaws provided with means adapted to effect both of these results; but my invention contemplates, broadly, the provision of means for accomplishing either of these results, and a modified form of device, also shown, is adapted to resist the backward tilting only.

In the drawings, Figure 1 shows a cross-section of a rail having secured to the base thereof a rail-stay constituting an approved embodiment of my invention. Fig. 2 shows in side elevation a portion of a rail and in cross-section its supporting-tie and a rail-stay of this form secured to the rail and abutting the tie. Fig. 3 is a plan view of the same. Fig. 4 is a sectional view, the section being taken on the line 4-4 of Fig. 1 looking in the direction indicated by the arrows. Fig. 5 shows in perspective the device detached from the rail, the connecting-bolt being omitted. Fig. 6 is a view similar to Fig. 1, but showing a modified form of rail-stay embodying my invention. Fig. 7 is a sectional view, the section being taken on the line 7-7 of Fig. 6. Fig. 8 is a perspective view of a rail-stay of this form detached from the rail, the connecting-bolt being omitted. Fig. 9 is a cross-sectional view of a further modification, and Fig. 10 is a broken elevational view of another modification.

In the several figures of the drawings, A is

the rail. B is the cross-tie upon which rests the base C of the rail A, the latter being spiked thereto in the usual manner. D and E are jaws adapted to grip the edges of the base C between them and to be drawn together by the bolt F. These jaws are provided with overhanging lips G and H, adapted to grip over the base of the rail. Extending downward from either or both of the jaws D and E is a lug I and J, these lugs being formed with surfaces adapted to abut against the tie B in the usual manner. Each of the jaws D and E is provided with an extension adapted to project inward or toward the other jaw and to overlap each other. In the form of the device shown in Figs. 1 to 5, inclusive, these extensions are given a U-shaped cross-sectional form, one being made smaller than the other, so that these members may telescope one within the other. These telescoping members K and L also engage the lower side of the rail-base.

When the jaws are drawn together by the tightening of the nut f upon the bolt F, any tendency which these jaws have to rock will cause the extensions K and L to be more firmly pressed up into engagement with the base of the rail, the result of this being that the force exerted which tends to draw the jaws together is applied in such a way that tendency of the jaws to tip is minimized.

It will be readily seen that with older devices of this character it happens at times that a hasty or careless workman will apply the device so that the jaws are not exactly opposite each other, and consequently the bolt extends diagonally across the base of the rail. Therefore if the parts are so constructed that either of the jaws can be swung lengthwise of the rail until the bolt is brought squarely across the base of the rail any strain which tends to bring this about will result in loosening the grip of the jaws upon the rail-base; but with my improvement, in which the lower extensions of the jaws engage each other so as to provide longitudinal guides, such faulty application of the device becomes impossible.

In the form of device shown in Figs. 6, 7, and 8 the interengaging extensions are given the form of overlapping parts M and N. The mutually-engaging ends of these extensions are preferably given a form similar to that of the familiar scarf-joint. When this

device is applied to the base of a rail and the nut *f* upon the bolt *F* is tightened, the part *N* will be forced up into engagement with the base of the rail and the part *M* will be forced up against the lower side of the scarfed portion of the part *N* and also will engage throughout a portion of its length the base of the rail.

It will be observed that each jaw and its extension under the rail constitutes roughly a bell-crank lever, which is fulcrumed upon the edge of the base-flange of the rail. Consequently there is a tendency to rock upon the rail-base when the bolt is tightened, and the objection has been sometimes made that with some constructions of this type of anti-creeper this rocking tendency subjects the bolt to a vertical strain and interferes to some extent with the efficiency of the device. By overlapping the extended portions of the jaws I am enabled to give each jaw a longer horizontal bearing below the rail-base and to thereby practically dispense with any tilting strain and any consequent strain on the bolt or other objectionable result arising therefrom.

In Fig. 9 is shown a cross-sectional view of a further modified form of my invention. In this form of rail-stay the extensions *O* and *P* are given an inverted-U form. When the bolt *F* is tightened to force the jaws together, the part *P* is forced upward into closer engagement with the base of the rail and the part *O* is forced up against the part *P*. In this form of the device, as well as in that shown in Figs. 1 to 5, these extensions serve to maintain the jaws in alinement with each other and with the bolt *F*.

In Fig. 10 is shown a form of rail-stay in which but one of the jaws is provided with a depending part *J*, adapted to engage the tie. In this device the tightening of the nut *f* upon the bolt *F* tends to throw the extensions *K* and *L* up into engagement with the rail-base, so that the tilting of the jaws backward away from the rail is prevented, as in the other forms of the device.

I claim—

1. In a rail-stay, the combination of a pair of jaws adapted to grip the opposite edges of the base-flange of a rail, each of said jaws being provided with a horizontal portion which extends beneath the rail-base and which overlaps such horizontal extension of the opposite jaw, and means for holding said jaws in gripping engagement with the rail-base.

2. A rail-stay, comprising a pair of jaws each constructed to engage the upper and lower face of a rail-base, said jaws being arranged to grip the opposite edges of the rail-base and to overlap each other beneath the rail-base, and means for holding said jaws in gripping engagement with the rail-base.

3. A rail-stay, comprising a pair of jaws

adapted to engage the opposite edges of the base-flange of a rail, said jaws overlapping each other beneath the rail-base so as to be mutually guided in the line of movement at right angles to the length of the rail, and means for holding said jaws in gripping engagement with the rail-base.

4. In a rail-stay, the combination with a pair of jaws adapted to grip the base of a rail between them, each of said jaws having an overhanging lip and one of said jaws having a downwardly-extending member adapted to abut against the tie, of means adapted to draw said jaws toward each other, each of said jaws being formed with means thereon extending toward the opposite jaw, said means adapted to engage each other when the jaws are drawn together.

5. In a rail-stay, the combination with a pair of jaws adapted to grip the base of a rail between them, each of said jaws having an overhanging lip, and one of said jaws being formed with a downwardly-extending part adapted to abut against the tie, of means adapted to draw said jaws toward each other, each of said jaws being formed with means thereon extending toward the opposite jaw, said means adapted to engage each other and the bottom of the rail when the jaws are drawn together.

6. In a rail-stay, a pair of jaws adapted to hook over the opposite edges of a rail-base, means extending downward from a jaw and adapted to engage a tie and means for drawing said jaws toward each other and into engagement with the rail-base, each of said jaws having formed thereon a projection adapted to extend toward the other jaw beneath the rail, said projections engaging each other and the bottom of the rail when the jaws are drawn together and thereby preventing tilting of said jaws.

7. In a rail-stay, a pair of jaws adapted to hook over the opposite edges of a rail-base, means extending downward from a jaw and adapted to engage a tie and means for drawing said jaws toward each other and into engagement with the rail-base, each of said jaws having formed thereon a projection adapted to extend toward the other jaw beneath the rail, said projections engaging each other and the bottom of the rail when the jaws are drawn together and thereby preventing tilting of said jaws.

8. A rail-stay, comprising a pair of jaws adapted to hook over the opposite edges of a rail-base, each of said jaws having formed thereon an extension adapted to project toward the other jaw, said extensions adapted to overreach each other, means extending from one of said jaws to the other below said extension for drawing the jaws together, and means upon a jaw for contacting with a tie.

9. A rail-stay, comprising a pair of jaws adapted to hook over the opposite edges of a

5 rail-base, means extending from one jaw to the other below the rail-base for drawing said jaws toward each other, and means between said last-named means and the rail-base adapted to engage the base of the rail, said means extending toward each other from the jaws and overlapping each other.

10. A rail-stay, comprising, in combination, a pair of jaws adapted to hook over the edges of a rail-base, each of said jaws having formed thereon an extension adapted to project beneath the base of the rail toward the other jaw, and a bolt adapted, when tightened, to draw said jaws toward each other 25 and to force said extensions into contact with the base of the rail and with each other.

11. An anticreeping device for rails, comprising a pair of clamping-jaws adapted to grip over the opposite edges of a rail-base, 20 each of said jaws being provided with means extending toward the other jaw, said means being formed to have telescoping engagement with each other, and means for drawing said jaws toward each other.

25. 12. In an anticreeping device for rails, the combination of a pair of jaws arranged to grip over the edges of the rail-base, means for drawing said jaws toward each other, and means for maintaining said jaws in alinement with each other, said means comprising a projection formed integral with each jaw and adapted to overlap, beneath the rail, the corresponding projection on the other jaw.

13. In an anticreeping device for rails, the 40 combination of a pair of jaws adapted to grip over the opposite edges of the rail-base, each of said jaws having a projection formed

integral therewith and so disposed that said projections will engage each other beneath the rail-base and have sliding, longitudinal 45 movement, the one upon the other, as the jaws are brought together, and means adapted to tighten said jaws upon the rail-base.

14. An anticreeping device, comprising a pair of oppositely-disposed jaws adapted to 45 grip the base of a rail, each of said jaws being provided with a lug extending toward the other jaw beneath the rail, each of said lugs extending more than one-half the distance between said jaws and adapted to engage the 50 lug on the other jaw, and means for drawing said jaws toward each other to secure the device to the rail.

15. A rail-stay, consisting of jaws disposed to grip the rail between them and formed 55 with transverse extensions adapted to meet each other beneath the rail, one of said jaws being formed with a downward extension adapted to abut against a tie, and a bolt for drawing said jaws toward each other. 60

16. A rail-stay, consisting of jaws disposed to grip the rail between them and formed with downward extensions and with transverse extensions adapted to meet each other beneath the rail, said extensions overlapping 65 each other and adapted to maintain the jaws in alinement with each other, and a bolt for drawing said jaws together and into engagement with the rail.
